[57] CLAIM

The ornamental design for a central command deck in a toy vehicle system, as shown and described.

DESCRIPTION

FIG. 1 is a perspective view of a central command deck in a toy vehicle system showing my new design;

FIG. 2 is an elevational view of the left side thereof;

FIG. 3 is a top plan view thereof;

FIG. 4 is an elevational view of the front thereof;

FIG. 5 is an elevational view of the right side thereof;

FIG. 6 is an elevational view of the rear thereof, and,

FIG. 7 is a bottom plan view thereof.

The partial showing of the vertical element if FIGS. 2, 4 and 6 is for ease of illustration only.
